INTERNAL COMBUSTION ENGINE OF THE
LIQUID FUEL INJECTION COMPRESSION
IGNITION TYPE

Harry Ralph Ricardo, London, England

Application July 25, 1938, Serial No. 221,208
In Great Britain July 29, 1937

3 Claims. (Cl. 123—32)

This invention relates to improvements in or modifications of internal combustion engines as described and claimed in the present inventor's U. S. Patent No. 2,113,711. In an engine as there described and claimed, not more than 50% of the total volume of the combustion space is constituted by the chamber or pocket which lies outside the cylinder, together with the passageway through the plug member disposed in the mouth of this chamber, the remainder of the combustion space being constituted by the space between the face of the piston and the end of the cylinder, which space is increased locally adjacent to the orifice of the passageway through the plug.

According to the present invention the above-mentioned recess is formed so that it is substantially circular in plan and it is combined with a groove which runs into this recess and enters it tangentially as viewed in plan, the outer end of the groove being located where it will be opposite the orifice of the passageway through the plug member. Thus the gases after ignition of the charge in the external combustion chamber will pass through the passageway in the plug member into the groove and along this groove into the circular recess. By reason of the tangential entry of the groove into the recess, the gases as they pass through the groove into the recess will tend to be given a rotational swirl in the recess and the reference to the tangential entry of the groove into the recess is to be interpreted as including not only constructions in which the groove is substantially straight and has a center line which is tangential with respect to a circle having the axis of the recess for centre, but other constructions in which the groove is so formed that the gas flowing therethrough into the recess will enter the recess in such a direction as to tend to cause rotational swirl in the recess.

The invention may be carried into practice in various ways, but one construction according to the invention and a modification thereof are illustrated by way of example in the accompanying drawing, in which

Figure 1 is a section through the upper part of a cylinder, cylinder head and piston incorporating the present invention, the section being taken in a plane containing the cylinder axis.

Figure 2 is a plan of the cylinder barrel and piston shown in Figure 1 with the head removed, the position of the combustion chamber being indicated in chain line.

Figure 3 is a section on the line 3—3 of Figure 2, and

Figures 4, 5 and 6 are views similar to Figure 2, showing several modifications according to the invention.

In the construction, illustrated in Figures 1,

2 and 3, the engine comprises a cylinder block A containing a water-cooled cylinder liner A¹ within which reciprocates a piston B, the upper end of the cylinder being closed by a cylinder head C which is also water-cooled and contains 5 inlet and outlet ports controlled by valves, one of which is indicated at D.

Formed in the cylinder head so as to lie partly to one side of but to overlap the cylinder bore, is a sprocket C¹ the upper end of which is, as shown, approximately hemispherical, while its lower end, which lies adjacent to the cylinder bore, is of generally cylindrical form and contains a plug E having a flange E¹ engaged by a 10 screwthreaded ring E² which serves to retain the plug in place. The external contour of the plug conforms generally to the internal contour of the lower part of the pocket, the plug being formed, however, so that there is a small air 15 space between its circumferential surface and the surface of the cooled wall surrounding it, so that the transference of heat from the plug to the cooled surrounding wall is limited.

Formed in the plug is an approximately hemispherical recess E³ which, with the hemispherical 20 end of the pocket, forms an approximately spherical combustion chamber C², into which leads tangentially a passage E⁴ formed in the plug so that its lower end communicates with the cylinder bore.

Formed in the face of the piston B is a recess B¹ which, viewed in plan, is of circular form, the bottom of this recess B² being approximately flat and being curved up at its edges to run smoothly into the side B³ thereof. Also formed in the 25 face of the piston is a groove B⁴, one end of which runs tangentially into the recess as shown, while its other end lies immediately beneath the lower end of the passage E⁴, the floor of this groove being curved at its outer end, as shown 30 at B⁵, so as to lead the hot gases flowing through the passage E⁴ smoothly along the groove B⁴ into the recess B¹.

As will be seen, the longitudinal axis of the groove B⁴, if extended, passes approximately 35 through the axis of the piston and the arrangement is such that the hot gases flowing from the combustion chamber C² through the passage E⁴ will pass through the groove B⁴ into the recess B¹ in such a manner as to rotate about the 40 axis of this recess.

In the alternative construction indicated in Figure 4 a recess B⁵, similar in form to the recess B¹, is formed in the face of the piston B so as to be approximately coaxial therewith and a 45 groove B⁶ of the same general form as, but somewhat longer than, the groove B⁴ leads tangentially into the recess B⁵, the outer end of the groove B⁶ lying beneath the lower end of the 50 passage E⁴ leading from a combustion chamber

constructed and arranged similarly to the combustion chamber C^2 , but with the axis of the passage E^4 lying otherwise than in a radial plane containing the axis of the cylinder.

5 It will thus be seen that in this construction the axes of the passage E^4 and groove B^6 lie in a plane which is tangential to a circle having the axis of the cylinder for centre.

In this construction also the hot gases flowing 10 from the passage E^4 will pass along the groove B^6 so as to enter the recess B^5 tangentially and thus be caused to rotate about the axis of this recess.

The dimensions of the recess and groove may 15 vary to suit requirements. As an example of one constructional arrangement in which the diameter of the piston is 4.75 inches, however, the diameter of the recess, viewed in plan, may be 2.25 inches at its margin, which lies in the plane 20 of the piston face. The flat-bottomed floor B^2 of the recess may then be approximately 1.75 inches in diameter and the recess at this floor may have a depth of 0.40 inch. In a construction such as 25 that shown in Figures 1, 2 and 3 with the parts 30 having the above dimensions, the length of the groove, measured from the axis of the piston to the outer end of the groove where it lies adjacent to the periphery of the piston, may be approximately 2.25 inches, the groove having a 35 width of, say, 0.75 of an inch. In this construction also the distance of the axis of the recess B^1 from that diameter of the piston which coincides with the longitudinal axis of the groove B^4 may be, say, 0.75 of an inch, while the distance of this 40 axis from the diameter of the piston which lies at right angles to the diameter referred to above may be, say, 0.375 of an inch.

It is to be understood that the above is given 45 purely by way of example and that the dimensions of the recess and of the groove may be varied to suit requirements. Thus, for example, in some cases, while both sides of the groove viewed in plan are straight up to the point where the shorter side meets the circumference of the recess, the other side may be arranged so that if continued straight it would not meet the circumference of the recess, this other side being curved inwards from the point in the length of the groove where the first side meets the circumference of the recess towards the axis of the recess so as to run smoothly into the circumference of the recess. Thus, in such an arrangement, as shown for example in Figure 5, which is otherwise similar to Figure 4, the circumference 50 of the recess B^6 and the side of the groove which runs smoothly into that circumference when viewed in plan may be regarded as together constituting a curve of more or less volute or spiral form, the inner end portion B^8 of the 55 spiral which forms the greater part of the circumference of the recess being, however, if desired of constant radius, while the outer end portion B^9 , which constitutes one side of the groove, is straight. Alternatively, as shown for example 60 in Figure 6, the side B^9 of the groove B^7 , which runs smoothly into the circumference B^8 of the recess B^6 , may constitute a continuation of the spiral referred to; the opposite side B^{10} of the groove being similarly formed, when the groove 65 as a whole may be regarded as of spiral form running smoothly into the recess much in the same way as the outlet of a centrifugal pump

enters the blade chamber. In a further modification otherwise similar to Figure 6, the side B^{10} of the groove may be straight.

It is to be understood that where the external combustion chamber and plug are situated at the 5 side of the cylinder and not in the cylinder head, according to an alternative arrangement indicated in the specification of the above-mentioned U. S. Patent 2,113,711 the improved recess and groove according to the invention may then be 10 formed in the head of the cylinder, so that the gases issuing from the passageway through the plug will enter the groove and pass thence into the circular recess wherein these gases will tend to be imparted to them a rotational swirl about 15 the axis of the recess.

What I claim is:

1. An internal combustion engine of the liquid fuel injection compression ignition type comprising in combination a cylinder, a detachable 20 head for the cylinder, a piston in the cylinder, the opposed faces of the head and piston adapted to be disposed closely together at the end of the compression stroke of the piston, thereby reducing the clearance between them as far as is permitted 25 by mechanical clearance, a pocket-like combustion chamber formed and disposed externally of the cylinder and opening toward the same, a plug member arranged in the mouth of said chamber and having a passageway therethrough, 30 said passageway terminating in an orifice, a fuel jet device disposed in said chamber for delivering a charge of fuel towards a point in the wall of said chamber, a recess formed in one of the said opposed faces, said recess, which is open to the 35 cylinder bore, being so formed that it is substantially circular in plan and being combined with a groove which runs into said recess and enters it tangentially, the outer end of said groove being adapted to lie opposite to said orifice at least at the end of the compression stroke, 40 said recess with said groove constituting a local increase in the otherwise reduced clearance between the piston and cylinder head, the total combustion space available at the end of the compression stroke being comprised by the 45 volumetric content of the external chamber, the passageway through the plug, the recess and the remainder of the clearance between the face of the piston and the end of the cylinder, of which total combustion space not more than 50% is in the external chamber and the said passageway. 50

2. An internal combustion engine as claimed in claim 1, in which the side wall of the groove which meets the circumference of the recess at an acute angle is approximately straight, while the other side wall, which runs smoothly into the circumference of the recess, is for a part of its length measured from the outer end of the groove substantially straight and tangential to a circle 55 having the centre of the recess for axis, but of larger diameter than the recess, and thereafter is curved inwards towards the axis of the recess after the manner of a volute so as to merge 60 smoothly into the circumferential wall of the recess. 65

3. An internal combustion engine as claimed in claim 1, in which the side wall of the recess and that side wall of the groove which runs smoothly into the side wall of the recess together constitute a wall which, viewed in plan, is of spiral 70 or volute form.

HARRY RALPH RICARDO.
